GARMENT SUPPORTER

Filed Sept. 17, 1930

UNITED STATES PATENT OFFICE

FREDERICK J. ZIMMERER AND HENRY W. BAUER, OF MIDDLETOWN, CONNECTICUT, ASSIGNEES TO THE RUSSELL MANUFACTURING COMPANY, OF MIDDLETOWN, CONNECTICUT, A CORPORATION OF CONNECTICUT

GARMENT SUPPORTER

Original application filed May 17, 1930, Serial No. 453,200. Divided and this application filed September 17, 1930. Serial No. 482,512.

This invention relates to garment supporters, such as garters, suspenders, and the like, which include a strap ordinarily of textile material bent to form a loop from which a garment-engaging member is loosely suspended. More particularly, the invention is concerned with a supporter of the type referred to which includes improved means for adjusting the length of the loop in accordance with the requirements of the wearer. By way of example, a garter embodying the features of the invention will be described in detail, though it is to be understood that the utility of the invention is not limited to this particular supporter.

Women's garters as ordinarily constructed include a strap of elastic webbing secured at one end to a girdle or the like and bent to form a loop in which a stocking-engaging member is loosely suspended. Attached to the free end of the strap at one side of the loop is an adjusting device which consists of a plate and a clamping jaw. The strap at one side of the loop is led through the adjusting device and the loop may be adjusted to any desired length and the device set to hold the parts of the strap on opposite sides of the loop in the desired relation.

The adjusting device is made of metal and it represents a considerable item in the cost of the supporter. Since the strap passes through the device, the latter is wider than the strap and it has projecting ends which are likely to catch on other garments and tear them. Also, the metal device rusts in the course of time and when laundered is likely to stain the supporter and other garments with which it is in contact. When a garter of this construction is worn in such position as to support a stocking at the rear, the somewhat bulky adjusting device is likely to cause considerable discomfort to the wearer when seated.

The present invention is accordingly directed to the provision of a garment supporter which includes all of the advantages of adjustment of the ordinary supporter but can be made more cheaply and worn with complete comfort.

The new supporter includes a strap of elas-

tic webbing bent to form a loop in which the usual garment-engaging member is suspended in the ordinary manner. The strap is provided with a series of openings arranged in a lengthwise row and secured to the strap near its free end is a fastening element, preferably a flat plate of metal of H-shape, attached to the strap near the free end thereof by having one of its main bars inserted through an opening in the strap, after which a portion of the strap beyond the opening is bent back over the bar and secured to the remainder of the strap. The other main bar of the plate may be inserted in any selected opening in the strap at the other side of the loop and since the openings are fairly close together, a close adjustment may be obtained throughout a substantial range.

In order to strengthen and reinforce the strap at the openings to increase the life of the supporter, the strap is preferably woven so that warp threads which lie on either side of the line along which the openings are formed are crossed at the ends of the openings to form crotches in which the fastening element is received. Preferably in an elastic fabric which includes strands of rubber, a pair of these rubber strands are selected as the warp threads which are to be crossed and with this construction, it will be seen that the strain imposed on the strap by the fastening device is taken up by a pair of warp threads of rubber crossed in the manner described. These rubber threads also define the side edges of the openings and because of their elasticity, they tend to keep the openings from gaping or being distorted.

For a better understanding of the invention, reference may be had to the accompanying drawings, in which

Fig. 1 is a plan view of a portion of a garter constructed in accordance with the principles of the invention;

Fig. 2 is a side view thereof;

Fig. 3 is an enlarged plan view showing the manner of forming the openings in the strap;

Fig. 4 illustrates the method of securing one form of fastening or adjusting device to the strap;

Fig. 5 is a longitudinal sectional view through a portion of the garter showing the manner of use of this device;

Fig. 6 is a view similar to Fig. 5 showing a different means of attachment of the fastening device of the strap;

Fig. 7 is a view similar to Fig. 6 showing the normal position of the fastening device with the modified form of attachment to the strap;

Fig. 8 is a plan view of a fastening or adjusting device of still another construction;

Fig. 9 is a plan view of a portion of the strap of a modified construction; and

Fig. 10 is an enlarged plan view showing the manner of weaving the strap illustrated in Fig. 9.

Referring now to the drawings, the supporter includes a strap 20 ordinarily of elastic webbing. This strap is attached at one end of a girdle or other garment, and the free end is bent to form a loop 21 in which is loosely suspended a garment-engaging member generally designated 22. This member includes a metal loop 23 through which the strap is threaded, a button 24 and a loop 25 cooperating with the button to serve as a means for attaching the supporter to the stocking.

The strap is formed with a plurality of openings 26 lengthwise thereof and these openings are preferably in the form of buttonholes spaced apart a relatively short distance so as to provide a fairly exact adjustment. The openings or buttonholes may be produced in the weaving of the strap which includes warp threads 27 in the form of rubber strands. These warp threads are spaced apart and have other warp threads 28 of ordinary textile material between them. The openings 26 are formed between a pair of adjacent warp threads of rubber 27, and in weaving the openings, the warp threads 27 are led toward each other and crossed, as indicated at 29, to provide a crotch at one end of the buttonhole. At this point, the buttonhole is defined by a pair of the crossed threads of elastic material. Those portions of the elastic threads which are crossed also define the side edges 30 of the opening and at the other end of the opening, the threads are recrossed as at 31 and returned to their normal positions. At the ends of the buttonholes, the warp threads 28 which lie between the elastic strands 27 are led away from each other and each warp thread 28 is shifted outwardly toward the edge of the fabric by one thread, thus permitting the elastic strands to be brought into crossed relation and to lie side by side throughout the length of the buttonhole opening without causing distortion of the fabric. At each buttonhole, the filling strands 31 extend from the edges of the fabric to the

buttonhole and around the rubber strands 27 which define the edges of the opening.

The method of weaving the buttonhole above described provides a strong point in the fabric at each end of the opening where strains are imposed in the normal use of the supporter.

Various adjusting or fastening means may be provided for cooperation with the buttonholes to permit variation in the length of the loop 21, as for example, a button may be sewed to the strap near the free end thereof to be inserted at will in any selected opening at the other side of the loop. A fastening device of the type illustrated in Fig. 4 is preferable, however, since it is more durable than a button and is of less thickness so that its presence will not cause discomfort to the wearer.

This fastening device comprises a metal plate of H shape having main bars 32, 33 connected to a cross bar or neck 34. The bar 32 is somewhat wider than the bar 33 but of less width than the strap. This fastening device may be attached to the strap in various ways, as, for example, the bar 32 may be inserted through the opening 26 at the free end of the strap, after which the portion of the strap lying beyond the buttonhole is folded back as indicated at 35, and may be secured to the remainder of the strap by stitching 36. With this arrangement, the fastening plate is anchored to the end of the strap and accidental displacement is prevented. As illustrated in Fig. 5, the neck 34 of the fastening element is bent slightly so as to cause the bars 32 and 33 to lie in slightly spaced planes and preferably the bar 33 is curved along its longitudinal axis so that its free edge 37 lies substantially in the plane of the upper surface of the bar 32.

In assembling the supporter, a strap of the construction described is cut to the desired length and the fastening device secured in place at the free end of the strap by stitching or the like. This end of the strap is then threaded through the loop 23 forming a part of the garment-engaging member and the strap bent to form the loop 21, the bar 33 of the fastening device being inserted through any selected opening 26 in the strap at the other side of the loop. By reason of the bend in the neck 34, the bar 33 tends to lie flat against the face of the strap adjacent the opening through which the bar is inserted, and the curvature of the bar 33 causes the free edge of the bar to bear firmly against the face of the strap when tension is put on the strap, thus preventing accidental displacement. Should it be desired to vary the adjustment, the bar 33 is merely displaced from one opening and inserted in another at the desired point. Also, by reason of using an adjusting device of this construction, the garment-engaging member 22 may be taken from the

end of the supporter when the latter has to be laundered, and if desired, the adjusting element itself may be similarly removed from the end of the strap.

With the new construction, it will be apparent that the cost of the supporter is materially reduced over that of supporters formerly used since the simple metal plate which constitutes the fastening or adjusting device is much less expensive than the adjusting devices now ordinarily employed. The new adjusting device does not project outwardly beyond the edges of the supporter so that it cannot catch on other garments, and furthermore, there are no parts of this adjusting device that come in contact with the body of the wearer. Since the device is substantially flat, it does not cause discomfort to the wearer when seated.

An adjusting device of a somewhat similar construction is shown in Fig. 6 but in this form the bar 32' is of double width and its free edge 38 is preferably formed with clamping teeth. The bar 32' is bent upon itself and slipped over the end of the strap, after which the two parts are gripped together to force the teeth into the strap and thus connect the device permanently to the strap. In normal use, the adjusting device in this form is placed as indicated in Fig. 7, in which it will be seen that the strap 20 is bent back upon itself over the clamping edge of the device. Thus, a good connection between the strap and device is obtained and the device cannot be accidentally freed from the strap except with extreme difficulty.

In Fig. 8 there is shown a modified form of the device, in which the bar 32 is formed with an opening 39 through which the end of the strap may be threaded, being bent back upon the remainder of the strap and stitched thereto as illustrated in Fig. 4.

In Figs. 9 and 10, there is illustrated a modified form of strap which embodies the principles of the invention. This strap is made of a two-ply material and one ply is provided with a series of openings 26 defined by crossed warp threads of rubber 27'. Adjacent each opening are formed pockets 40, one on each side of the opening, these pockets lying between the two plies of the fabric. This type of strap may be employed with a fastening or adjusting device of the sort shown in Figs. 4 to 8, inclusive. When the fastening element illustrated in Fig. 4 is used the bar 32 may be inserted in a pocket at one side of the loop and the bar 33 inserted in any selected pocket at the other side of the loop. The element is then held in position without the use of stitching and this permits ready removal of the element when the supporter is to be laundered. Stitching may be used if desired, however. When the device is in use, the bar 33 is inserted through an opening 26 in the upper ply and the bar lies in the pockets between the

two plies. This construction produces a somewhat stronger strap and the bar 33 of the adjusting device is wholly concealed in the pockets. The strap illustrated in Figs. 9 and 10 is not substantially different from that shown in Fig. 1 except that an extra ply of material is present and the openings 26 are formed in one ply only instead of being formed through both plies.

This application is a division of our co-pending application Ser. No. 453,200, filed May 17, 1930, which has now matured into Patent No. 1,800,671, issued April 14, 1931.

What we claim:

1. A garment supporter which comprises an elastic textile strap including rubber warp threads and bent upon itself to form a loop, the strap having a series of openings therein in a lengthwise row, each opening being defined at at least one end by crossed rubber warp threads providing reinforcement, a garment-engaging member mounted loosely in the loop, and a fastening element secured at one end to the strap and having a portion insertable at will in any opening in the other side of the loop to vary the length thereof, said element being H-shaped.

2. A garment supporter which comprises a fabric strap bent upon itself to form a loop, this fabric being double ply and having a series of spaced separate pockets formed between the plies and an opening through one ply into each pocket, said openings being elongated and defined by warp threads crossed at the ends of the openings to provide reinforcement a garment-engaging member loosely suspended in the loop, and a fastening element having a portion in a pocket at one side of the loop and another portion in a pocket at the other side of the loop.

3. A garment supporter which comprises an elastic fabric strap including rubber warp threads and bent upon itself to form a loop, this fabric being double ply and having a series of spaced separate pockets formed between the plies and an opening through one ply into each pocket, said openings being defined by rubber warp threads crossed at the ends of the openings to provide reinforcement a garment-engaging member loosely suspended in the loop, and a fastening element of metal having one end anchored in a pocket at one side of the loop and its other end anchored in a pocket at the other side of the loop.

4. A garment supporter which comprises an elastic strap including rubber warp threads and bent upon itself to form a loop and having a row of openings therein, each opening being reinforced at its ends by crossed rubber warp threads a garment-engaging member loosely suspended in the loop and a fastening element having a portion gripping the strap at its free end, and another part receivable optionally in any selected

opening in the strap to vary the length of the loop.

5. A garment supporter which comprises a strap bent upon itself to form a loop and having a row of openings therein, a garment-engaging member loosely suspended in the loop, and a fastening element of H-shape having one side bar secured to the strap and the second side bar insertable optionally in any selected opening in the strap to vary the length of said loop, the connecting bar of said element being bent to cause the said side bars to lie in different planes and one of said side bars being bent along its longitudinal axis so that its free edge lies substantially in the plane of said first side bar.

In testimony whereof we affix our signatures.

FREDERICK J. ZIMMERER.
